UNITED STATES PATENT OFFICE.

WALTER CLYDE JONES, OF CHICAGO, ILLINOIS, ASSIGNOR TO GARTON-
DANIELS COMPANY, OF KEOKUK, IOWA, A CORPORATION OF IOWA.

LIGHTNING-ARRESTER.

No. 811,226.

Specification of Letters Patent.

Patented Jan. 30, 1906.

Application filed December 7, 1901. Serial No. 85,082.

To all whom it may concern:

Be it known that I, WALTER CLYDE JONES, a citizen of the United States, residing at Chicago, in the county of Cook and State of Illinois, have invented a certain new-and useful Improvement in Lightning - Arresters, of which the following is a full, clear, concise, and exact description, reference being had to the accompanying drawings, forming a part 10 of this specification.

My invention relates to improvements in protective devices designed to guard electrical apparatus, and especially dynamo-electric machinery, from the destructive effects of lightning discharges and excessive currents in light and power circuits. It has particular reference to that class of arresters or protective devices that employ electromagnets responsive to an excess flow of current in the 20 arrester branch to open or otherwise affect the circuit and thereby cause a cessation of current in the said branch. In devices of this type the operating-magnet is ordinarily shunted by a non-inductive resistance to permit the lightning or similar discharge to pass around the same, as the magnet has an impeding effect upon the discharge and at the same time is liable to be burned out and destroyed thereby. It has also been the practice to place a resistance in series with the lightning-arrester beyond the point of juncture of the said multiple branches to cut down the current flowing through the magnet to thereby prevent the same from being too violently 30 actuated upon the passage of a discharge, as otherwise the magnet would attract its core with such force as to break the insulating-base upon which the same is mounted, said base being usually made of slate, porcelain, or the like. The practical embodiment of this form of protector or arrester as now employed comprises a graphite rod suitably connected in the circuit of the arrester branch by terminals at its ends and a further contact-terminal located intermediate its ends and ordinarily placed nearer the grounded end of the rod. The operating-magnet is then connected between the intermediate terminal and the line end of the rod, whereby there results 40 a portion of the graphite rod in parallel with the operating-magnet and the remainder of the rod in series in the ground branch, or, in other words, in series with both branches. This plan, however, has its practical objections.

The series portion of the rod is obliged to 55 carry the whole current of the branch, and thus in time becomes overheated and changes its character and deteriorates and disintegrates. It is also a difficult matter, if not impossible, to secure a contact with graphite 60 that does not in time become defective when carrying a large amount of current, such as accompanies a lightning discharge. The result is that the whole rod must after a period 65 of use be thrown away and a new one substituted when only the one end is defective—that is, the series end, which has been subjected to the greater work by having to carry all the current, while the shunt end has to carry only a shunted portion of the current. 70

My invention is designed to overcome these objections and to provide an improved form of arrester in which the graphite resistance shall not be subjected to such powerful currents and in which the current therethrough 75 is uniform from end to end, whereby the rod is capable of long life and uniform deterioration, the expense of maintenance and repairs being thereby greatly reduced.

Other and numerous advantages will appear 80 from the detailed description.

In the drawings, in which the same reference characters represent like parts throughout, Figure 1 is a front elevation of an arrester or protector embodying my improvements. 85 Fig. 2 is a side view thereof. Fig. 3 is a front elevation showing some of the operative parts in section, the resistance in series in the coil branch consisting of a coil of wire rather than a graphite rod. Fig. 4 illustrates a diagram 90 of the device of Fig. 1, and Fig. 5 is a like view of the modification of Fig. 3.

I have illustrated my invention in connection with a well-known type of arrester for the purpose of explanation, and it will be understood that my invention is equally applicable to other forms of arresters.

In the figures, *a* denotes an insulating-base, preferably of slate, on which the other parts of the arrester are mounted. These comprise the electrodes *b b'*, of carbon or other suitable material, separated by a small air-space to form the spark-gap and mounted in brackets *c c'*, set-screws or binding-screws *d d'* being employed to secure them rigidly in position. The 100 lower brackets *c* has a portion *c''*, serving as a binding-post to receive the ground branch *g*. A fiber tube or other suitable insulating-tube

e is mounted at the lower end in the bracket *c'* and is carried at its upper end in the similar bracket *f*. The electrode *b'* is adapted to fit within the lower end of the fiber tube *e*, and both may be fixedly secured in the bracket *c'* by the set-screw *a'*. A magnet-coil *h* is carried upon and surrounds the tube *e* and is adapted to actuate a core *h'*, located within said tube and capable of moving longitudinally therein. The core is adapted to normally rest upon the upper end of electrode *b'*, as shown in Fig. 3. The core carries a rod *h''*, extending from its upper end out at the top of the tube *e*, this rod being preferably of brass, though other material may be used. Upon the base *a* at one side of the tube the non-inductive resistance *k*, which is preferably a graphite rod, is mounted in suitable terminal or contact clips or brackets *k' k''*, the said brackets being adapted to be secured to the said base by screws in the usual way, and the lower one being provided also with a binding-post and screw *k''* to receive the branch wire from the line or circuit to be protected. Another resistance bar or rod *o* is likewise mounted in suitable terminal brackets, as shown in Fig. 1. Suitable channels or grooves are formed in the back of the base, and wires or connectors are placed therein to connect the various parts. One end of the magnet-coil is connected by wire *p* with binding-post *k''* and the other end by wire *r* with resistance *o*, the wire *s* joining *o* to bracket *k''*, while conductor *t* extends to the point or aperture *r* in the base. From this point a flexible wire *t'* connects the wire *t* to the end of the rod *h''*. The electric circuits of this form are shown more clearly in Fig. 4. The live wire *w* is connected by a branch *w'* with the binding-post *k''* on the base-plate of the arrester. A lightning or similar discharge on the line-wire *w* will seek the path through wire *w'*, post *k''*, rod *k*, wires *t' t'*, rod *h''*, core *h'*, electrode *b'*, thence jumping across the air-gap to electrode *b*, and thence over branch *g* to ground. Although the resistance of rod *k* is high, it is non-inductive in character, and the discharge will pass through it in preference to passing through the coil of the magnet *h*, which is inductive and offers impedance to the passage of the discharge. As soon as the arc is established across the spark-gap a comparatively low resistance-path for the line-current is furnished and it at once follows the path of the discharge in large volume. This current, however, being continuous in character will pass through magnet *h* more freely. The magnet or solenoid will become energized, drawing up its core and lifting the core *h'* from contact with the electrode *b'*, thus opening the circuit and stopping the flow of current in the branch from the line through the instrument to ground. The flow of current being stopped, the arc between the electrodes *b* and *b'* ceases or is starved out, so to speak,

so that upon the falling of the core as soon as the magnet is deenergized the circuit will again be opened at the electrodes and the instrument is in position to act in the same way upon the passage of another discharge. In order to cut down the current in the magnet and to avoid using one end of the graphite rod, as in the construction above alluded to, I place a resistance *o*, which may be of the same material as the rod *k*, in the magnet branch, as shown in Figs. 1 and 4. By this means the magnet is not subjected to a larger current than it can safely stand and the suddenness and force of its operation may be readily adjusted. By this arrangement also neither rod receives the full force of the current, so that both are capable of a long life and the contacts connected therewith do not deteriorate rapidly. When either rod is incapable of further use, it alone is replaced without reference to the other.

In the modification of Figs. 3 and 5 the resistance-rod *o* in the magnet branch is omitted and a resistance-coil *o'* is substituted therefor. This may well be done, for the inductive effect of the same is an advantage in this path rather than an objection. When this form is used, the coil is advantageously placed between the magnet and the grounding, so that the latter will protect it from the lightning discharge. This resistance may be of fine wire of high resistance and is preferably wound upon a porcelain or insulated iron core, the whole then being covered with a porcelain or enamel insulation in a well-known manner.

In Fig. 5 the core *h'* is shown lifted above the electrode *b'*, as when the magnet is operated.

By the term "operating-magnet" as employed herein I contemplate any magnet of a lightning-arrester employed to check the excessive flow of current following a discharge, whether by magnetically blowing out the arc, mechanically separating the electrodes, opening the circuit to starve the arc, or in any other manner.

Having described my invention, what I claim as new, and desire to secure by Letters Patent, is—

1. In a lightning-arrester, the combination of two continuous paths for the current, non-inductive resistance arranged in one of said paths, and an arrester-coil and a resistance arranged in the other path, substantially as described.

2. In a lightning-arrester, the combination of two continuous paths for the current, non-inductive resistance arranged in one of said paths, and an arrester-coil and an inductive resistance arranged in the other path, substantially as described.

3. In a lightning-arrester, the combination with two continuous paths for the current, of non-inductive resistance arranged in one of

said paths, and an arrester-coil and a resistance-coil arranged in the other path, said latter resistance being located between the arrester-coil and the ground, whereby the resistance-coil protects the arrester-coil from the effect of lightning discharges.

4. In a lightning-arrester, the combination with two continuous paths for the current, of a graphite rod constituting a non-inductive resistance located in one of said paths, an arrester-coil and an inductive resistance located in the other path, substantially as described.

5. In a lightning-arrester, the combination with two continuous paths for the current, of an arrester-coil and an inductive resistance located in one of said paths, a pair of clamping

devices and a graphite resistance-rod clamped therein, said clamps and graphite rod constituting a part of the second parallel path, substantially as described.

20

6. In a lightning-arrester, the combination with arcing electrodes, of an arrester-coil, a non-inductive resistance in shunt of said arrester-coil, and a resistance in series with said coil.

25

In witness whereof I have hereunto subscribed my name in the presence of two witnesses.

WALTER CLYDE JONES.
